US00D748072S

(12) **United States Design Patent**
Jones(10) **Patent No.:** **US D748,072 S**
(45) **Date of Patent:** **** Jan. 26, 2016**(54) **SOUND BAR AUDIO SPEAKER**(71) Applicant: **Emo Labs, Inc.**, Waltham, MA (US)(72) Inventor: **Terrence Keith Jones**, Sharon, MA (US)(73) Assignee: **Emo Labs, Inc.**, Wellesley, MA (US)(***) Term: **14 Years**(21) Appl. No.: **29/484,920**(22) Filed: **Mar. 14, 2014**(51) LOC (10) Cl. **14-01**

(52) U.S. Cl.

(57) **CLAIM**
The ornamental design for a sound bar audio speaker, as shown and described.

DESCRIPTION

FIG. 1 is a front perspective view of embodiment one, of a sound bar audio speaker, showing my new design.

FIG. 2 is a front view thereof.

FIG. 3 is a back view thereof.

FIG. 4 is a left side view thereof.

FIG. 5 is a right side view thereof.

FIG. 6 is a top plan view thereof.

FIG. 7 is a bottom plan view thereof.

FIG. 8 is another front perspective view thereof.

FIG. 9 is another front view thereof.

FIG. 10 is another rear view thereof.

FIG. 11 is another right side view thereof.

FIG. 12 is another top plan view thereof.

FIG. 13 is another bottom plan view thereof.

FIG. 14 is a partially enlarged view thereof, taken along the lines 14 of FIG. 8.

FIG. 15 is a partially enlarged view thereof, taken along the lines 15 of FIG. 9.

FIG. 16 is a partially enlarged view thereof, taken along the lines 16 of FIG. 10.

FIG. 17 is a right side view thereof, shown in an enlarged scale, taken along the lines 17 of FIG. 11.

FIG. 18 is a partially enlarged view thereof, taken along the lines 18 of FIG. 12.

FIG. 19 is a partially enlarged view thereof, taken along the lines 19 of FIG. 13.

FIG. 20 is a front perspective view of embodiment two, of a sound bar audio speaker, showing my new design.

FIG. 21 is a front view thereof.

FIG. 22 is a back view thereof.

FIG. 23 is a left side view thereof.

FIG. 24 is a right side view thereof.

FIG. 25 is a top plan view thereof.

FIG. 26 is a bottom plan view thereof.

FIG. 27 is another front perspective view thereof.

FIG. 28 is another front view thereof.

FIG. 29 is another rear view thereof.

FIG. 30 is another right side view thereof.

FIG. 31 is another top plan view thereof.

FIG. 32 is another bottom plan view thereof.

FIG. 33 is a partially enlarged view thereof, taken along the lines 33 of FIG. 27.

FIG. 34 is a partially enlarged view thereof, taken along the lines 34 of FIG. 28.

FIG. 35 is a partially enlarged view thereof, taken along the lines 35 of FIG. 29.

FIG. 36 is a right side view thereof, shown in an enlarged scale, taken along the lines 36 of FIG. 30.

FIG. 37 is a partially enlarged view thereof, taken along the lines 37 of FIG. 31; and,
FIG. 38 is a partially enlarged view thereof, taken along the lines 38 of FIG. 32.

The broken line portions of FIGS. 1-38 are included to show unclaimed subject matter only and form no part of the claimed design.

The dot-dash broken line portions of FIGS. 8-16, 18, 19, 27-35, 37, and 38 are included to show partly enlarged views only and form no part of the claimed design.
